DESIGN FOR A PNEUMATIC CUSHION

Frank G. Manson, Dayton, Ohio

Application September 9, 1937, Serial No. 71,527

Term of patent 3½ years

To all whom it may concern:

Be it known, that I, Frank G. Manson, a citizen of the United States, residing at Dayton, county of Montgomery, and State of Ohio, have invented a new, original, and ornamental Design for Pneumatic Cushion, of which the following is a specification, reference being had to the accompanying drawing, forming part thereof, wherein:

Figure 1 is a perspective view of a pneumatic cushion, showing my new design.

Figure 2 is a view in cross section on the line 2—2.

I claim:

The ornamental design for a pneumatic cushion substantially as shown.

FRANK G. MANSON.
